UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,960, dated July 1, 1890.

Application filed April 15, 1890. Serial No. 348,118. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 The drawing illustrates an elevation of a cane or umbrella handle embodying my new design, in which—

A is the body part, B the head or cap, and C the base. The body part A is formed with 15 an enlarged upper portion terminating in a plain cap B and a contracted lower portion relieved by ornamentation E. The body is, furthermore, made with ribs D, extending

vertically. The base C is made with a swelling annular central portion formed with vertical ribs G, and is bounded above by a plain band F and below by a similar band H.

20 The handle may be made of any suitable material.

Having now described my new design, what I claim as new, and desire to secure by Letters Patent, is—

25 The design for umbrella or cane handles, substantially as herein described and shown.

30 In testimony of which invention I have hereunto set my hand.

HENRY O. SCHMIDT.
